(57) **CLAIM**

The ornamental design for an information handling system rack enclosure, as shown and described.

DESCRIPTION

FIG. 1 is a front perspective view of the information handling system rack enclosure comprising the present invention;

FIG. 2 is a front view thereof;

FIG. 3 is a right side view thereof;

FIG. 4 is a left side view thereof;

FIG. 5 is a back view thereof; and,

FIG. 6 is a top view thereof.

Broken lines shown in the drawings illustrate portions of the information handling system rack enclosure, and form no part of the claimed design.
